UNITED STATES PATENT OFFICE.

LESTER L. LADD, OF LOCKPORT, ILLINOIS.

LABELING MACHINE.

1,227,158.

Specification of Letters Patent. Patented May 22, 1917.

Application filed December 1, 1913. Serial No. 303,891.

To all whom it may concern:

Be it known that I, LESTER L. LADD, a citizen of the United States, residing at Lockport, county of Will, State of Illinois, have invented a certain new and useful Improvement in Labeling-Machines, and declare the following to be a full, clear, and exact description of the same, such as will enable others skilled in the art to which it pertains to make and use the same, reference being had to the accompanying drawings, which form a part of this specification.

When paper is moistened it expands in the direction of the grain although no appreciable change takes place across the grain. This characteristic has made the problem of applying labels of any considerable size a difficult one so that in many lines of industry receptacles of various kinds are labeled by hand and, in others, where the labeling is done by machinery there is only a partial attachment of the labels along a few lines or spots in order to avoid the moistening of the main body of the label.

The object of my invention is to produce a simple and efficient machine for securely attaching labels in such a manner that there will be a union between all portions of the label and the thing to which the label is attached, and the label will lie smooth and even.

A further object of my invention is to produce a simple and efficient machine for applying a label to a can or the like having its ends closed with flanged caps, making the label long enough to overlap the caps and effectively seal the receptacle.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front elevation of a machine arranged in accordance with a preferred form of my invention;

Fig. 2 is a side elevation looking toward the right in Fig. 1, one end of the machine being broken away;

Fig. 3 is a top plan view of that portion of the machine illustrated in Fig. 2, the label feeding mechanism being omitted;

Fig. 4 is a view similar to Fig. 3 of the opposite end of the machine;

Fig. 5 is a view looking upwardly from the bottom of Fig. 4, being an edge view of one end of the machine;

Fig. 6 is a section on an enlarged scale 60 taken approximately on line 6—6 of Fig. 3;

Fig. 7 is a section on an enlarged scale taken in part on line 7—7 of Fig. 3 and in part on line 7a—7a of Fig. 3;

Fig. 8 is a top plan view of the label feeding mechanism;

Fig. 9 is a section taken approximately on line 9—9 of Fig. 8;

Fig. 10 is a section on line 10—10 of Fig. 8;

Fig. 11 is a plan view of a fragment of the shafting and clutch mechanism;

Fig. 12 is a view looking upwardly from the bottom of Fig. 11;

Fig. 13 is a detail of a device for tilting cans to be labeled into the machine;

Fig. 14 is a section through one of the bearings for the brush which partially attaches each label to a can;

Fig. 15 is a side view of the lifting cam shown in Fig. 6; and

Fig. 16 is a side view of the lifting cam shown in Fig. 7.

In the drawings I have illustrated a single successful embodiment of my invention adapted particularly to apply labels to round cans closed at the ends with flanged paper caps, the labels being long enough to overlap the flanges on the caps and effectively seal the cans; and, for the sake of brevity I shall confine the detailed description to this particular embodiment and shall refer to the things to be labeled as cans, intending by the use of the word "cans" to include anything which may be labeled in accordance with my invention.

Briefly stated, my invention is based on the theory that if the moisture in a paste-covered label is permitted to soak into the label before it is attempted to apply the label permanently, the paper is given an opportunity to stretch so that if it is laid smoothly about a can it will remain smooth and securely attached upon drying. In accordance with my invention I partially attach a paste-covered label to a can along a line parallel with the grain of the paper; allow sufficient time for the moisture to soak into the paper; and then complete the attachment of the label.

In the embodiment of my invention illustrated, I employ a horizontal endless con-

veyer having thereon separated seats for receiving cans to be labeled, together with means for attaching one end of a paste-covered label to each can when it reaches a predetermined point, and other means for thereafter wrapping the label completely around the can; the length of the conveyer and the timing being such that the moisture has time to soak into the label before the final wrapping operation takes place.

Reference being had to the drawings, 1 represents an endless horizontal chain passing around separated horizontal sprocket wheels, 2 and 3, the sprocket wheel 2 being the driving member and the other sprocket wheel an idler. Upon the chain are secured separated can-receiving seats, 4, spaced at equal distances apart. In the arrangement shown, the seats are in the form of semi-circular troughs formed of two connected semi-circular pieces. Just behind each of the seats, having reference to the direction of movement of the chain, and preferably secured to the seat, is a horizontal apron, 5, having a width somewhat less than the length of the cans to be operated upon and a length sufficient to support the trailing end of a label pasted at its front end upon a can in the corresponding seat. Beneath the two main parallel portions of the chain are tracks or guides, 6, upon which the seats or parts attached thereto may ride so as to prevent the chain from sagging. Following along the outside of the chain 35 is a guide, 7, in the proper plane to engage with the outer ends of cans, 8, resting in the seats. Additional guides, 9, similar to the guides 7 are arranged along the inner sides of the main portions of the chain, the guides 40 9 being adapted to engage with the inner ends of cans resting in the seats. In order that cans of different lengths may be worked upon I prefer to make the inner guides 9 adjustable, this being accomplished in the arrangement 45 illustrated by supporting the guides 9 on horizontal rods or stems, 10, which are lengthwise adjustable in suitable stationary bearings, 11.

The cans to be labeled may be fed to the machine in an upright condition by a suitable belt, 12, ending in proximity to the driving sprocket wheel 2 and, after the cans have been labeled, they may be delivered to a belt or conveyer, 13, which carries them away, the belt or conveyer 13 being conveniently arranged adjacent to the main driving sprocket at an angular distance from the delivery belt equal to the distance between consecutive seats on the main conveyer. This arrangement permits a can to travel a distance approximately equal to the length of the conveyer between the time it is received and the time it is discharged.

Just between the delivery belt 12 and the main conveyer is hung a shelf, 14, having

along the front edge an upwardly-projecting flange, 15. The cans to be labeled are fed forward by the belt 12 until the innermost can strikes the flange 15 on the swinging shelf. As will hereinafter be explained in detail, the main conveyer is moved intermittently through successive steps each equal to the distance between consecutive seats, and the parts are so proportioned that whenever the main conveyer comes to rest one of the seats lies directly in line with the delivery belt, 12. While the conveyer is at rest the swinging shelf is tilted so as to lay the foremost can on the delivery belt into the adjacent empty seat. On the rear edge of the tilting shelf is a depending flange, 16, curved in an arc concentric with the swinging axis of the shelf and serving to arrest the forward movement of the second can while the first is being delivered to the conveyer.

As near the receiving point as possible, is placed a label coating and feeding mechanism for delivering paste-covered labels one at a time and partially attaching them to the cans as the latter travel past on the conveyer. As best shown in Figs. 3 and 6 there is arranged just above the conveyer, as it leaves the driving sprocket, a rotary brush, 18, of a length as great as the length of the cans and revolving about an axis parallel with the axis of a can lying in the adjacent seat on the conveyer. The parts are so proportioned that whenever the conveyer is at rest one of the seats lies below and slightly behind the brush. The purpose of the rotating brush is to attach the advance end of a paste-covered label to a can. Unless the advance edge of the usual rectangular label is placed exactly parallel with the axis of the can, the subsequent wrapping of the label will cause it to form a spiral. Since it is impracticable to make the conveyer with such nicety as to insure that each can will be alined just right beneath the rotating brush, I have provided a cradle, 19, having portions lying on opposite sides of the paths of movement of the can seats and provided with four separated rollers, 20, on which each can may be accurately supported when the cradle is raised high enough to lift the can out of its seat and bring it into contact with the brush. In the arrangement shown, the cradle is carried upon the end of a long swinging frame, 21, provided at its free end with a downwardly-projecting arm, 22, which is acted upon by a suitably shaped and suitably timed cam, 23, so as to cause the cradle to rise whenever the conveyer comes to rest and to recede again before the conveyer again starts to move.

The paste delivery apparatus comprises a table, 25, arranged above and in rear of the rotating brush at an angle which brings it approximately tangential to the lower portion of the brush. The table is made wider

than the brush so as to leave room for a stack of labels and also an unobstructed portion bounded by adjustable guides, 26, in line with the brush and adapted to receive labels one at a time and allow them to slide downwardly. Between the table and the rotary brush are three sets of revolving rolls arranged one in advance of the other and having a common plane of contact forming a continuation of the plane of the table top. In the arrangement shown, the set of rolls nearest the table comprises a lower cylinder, 27, and an upper member made up of a series of disks, 28, suitably fixed upon the shaft 29. The second set of rolls comprises a member, 30, similar to the member 27 of the first set and a series of disks and an upper member made up of disks, 31, on a shaft, 32. The disks 28 may have an appreciable thickness but I prefer to make the disks 31 either very thin or else bevel them at the edges so as to present a minimum peripheral surface. The roller 30 extends into a paste-containing well, 33, the well being preferably kept filled to a constant level above the lowermost point of the roller so that when the roller revolves it carries paste upwardly with it. The third set of rolls, those nearest the rotary brush, may conveniently take the form of disks, 34, mounted on suitable shafts, 35. Extending transversely of the rollers from the first set to a point near the rotating brush are two sets of parallel rods, 37, and 38; the rods 37 preferably lying in peripheral grooves, 39, in the rollers 27 and 30 and passing between the disks of the lower roller of the third set; and the rods 38 being arranged between the disks of the upper rollers. The rollers are suitably driven in the proper direction and at the proper speed to feed a label delivered to the first set of rollers from the table toward the rotary brush at a speed slightly greater than the speed at which the main conveyer moves; the rollers starting and stopping in synchronism with the main conveyer.

Referring to Fig. 6 it will be seen that, the machine being in operation, if one of a stack of labels, 40, is laid between the guides 26 on the table it will slide down between the first set of rolls and will be fed by the same between the guiding rods or wires to the second set where its under side comes in contact with the paste-covered pasting roller 35 and is coated with paste. The label continues its forward movement between the third set of rollers until its advance end is delivered beneath the rotating brush. Assuming that the conveyer has just come to rest with a can in the seat below the rotating brush: The cradle 19 rises, centers the can and presses it up against the rotating brush, the can lifting the overlying end of the label during this operation so that the label is pressed between the can and the rotating

brush while its rear end is being held between the now stationary feeding rollers. The brush revolves in the direction tending to draw the label out of the rollers and thus attaches it while under tension, insuring that the label will be accurately positioned on the can. The parts are so proportioned that when the advance end of a label is in position to be attached to a can the rear end of the label has passed the first set of rollers, leaving these latter rollers in a condition to receive the next label which the attendant simply places on the table between the guides and allows to slide down between the rollers where it will be grasped and fed forward as soon as the rollers again start. By making the rollers of the label-delivering mechanism feed the label slightly faster than the cans in the conveyer travel, there is no danger that labels will become torn when the conveyer starts and the rear end of a label attached to a can is still held between the rollers. After the advance end of the label has been securely attached to the can, the supporting cradle recedes and allows the can to settle back into its seat. Then when the conveyer starts forward, the trailing end of the label is fed out between the rollers of the label-delivering mechanism and finally drops upon the apron attached to the seat just behind the can, lying flat and being held out of contact with other parts of the machine. The can with its partially attached label travels forward step by step until it approaches the discharging point. During this time the moisture in the paste soaks into the label, permitting the label to stretch. As I have heretofore explained, the paper stretches across the grain and not appreciably in the direction of the grain and therefore the labels should be cut so that the grain runs in the direction of the length of the can and therefore the expansion in the narrow strip which is initially pasted upon the can is entirely across its shortest dimension and is therefore of no consequence.

Just before the discharge point is reached the label is completely wrapped around the can. The mechanism for this purpose is best illustrated in Figs. 2, 3 and 7. At a distance from the discharge belt 13 equal to the space between two consecutive seats on the conveyer is arranged a cradle, 41, similar to the cradle 19, the cradle 41 having four separated rollers, 42, for lifting the partially labeled can from its seat and delivering it to mechanism for completing the labeling. The cradle 41 is supported at one end of a long swinging frame, 43, having at its free end a cam roller, 44, adapted to be engaged by a cam 45 which comes into play to lift the cradle whenever the conveyer comes to rest. Just above the cradle are arranged two short aligned shafts, 46 and 47, having on their adjacent ends

shallow cups, 48 and 49, respectively, these cups being of a size and shape to receive the ends of a can. The shafts 46 and 47 are arranged in suitable bearings, 50, which permit the shafts to rotate and at the same time be moved from and toward each other. Fixed to the shaft 46 is a collar, 51, connected to the upper end of an oscillatory lever, 52, in such a manner that the collar 51 may rotate relative to the lever but is required to move with the lever in the direction of the length of the shaft. A spring, 53, tends normally to swing the lever 52 in the direction to draw the shaft 46 away from the shaft 47. On the shaft 47 is a collar, 54, similar to the collar 51 but loose on the shaft. The oscillatory lever 55 similar to the lever 52 is connected to the collar in the same way that the lever 52 is connected to the collar 51. On opposite sides of the collar 54 and spaced apart therefrom are collars, 56 and 57, fixed to the shaft 47. Between the collars 54 and 56 is a spring, 58. Between a stationary part and the collar 54 is a second spring, 59. The spring 58 tends to thrust the shaft 47 toward the other shaft, the collar 54 acting as an abutment; while the spring 59 tends to press the collar 54 toward the collar 57. The result is that whenever the lever 55 is free so as to permit the spring 59 to act, the spring presses collar 54 against the collar 57 and then causes both of these collars to move in the direction to carry the shaft 47 away from the shaft 46, swinging the upper end of the lever outwardly. When the lever is actuated so as to swing the upper end inwardly against the tension of the spring 59 it moves the shaft 47 yieldingly toward the shaft 48. The levers 52 and 55 are provided with cam rolls, 60 and 61, engaged by suitable similar cams, 62, which may conveniently be fixed to the shaft 63 on which the cradle actuating cam, 45, is mounted. The parts are so proportioned and timed that when the conveyer comes to rest the cam 45 lifts the cradle so as to bring the can directly between the two cup-shaped members 48 and 49, these now being held apart by the springs 62 acting on the levers 52 and 55. As soon as the can is raised the cams 62 act on the levers 52 and 55 so as to throw the shafts 46 and 47, and the members 48 and 49 thereon toward each other; gripping the can between the members 48 and 49. By having a spring between the lever 55 and the shaft 47, this shaft will be yieldingly pressed so as to compensate for inequalities in the lengths of cans and permit each can to be firmly grasped. As soon as the can is gripped by the members 48 and 49 the cradle 41 recedes and thereafter remains idle until the conveyer has been set in motion and again come to rest after having completed another step. One

of the shafts 46 and 47, preferably the shaft 46, is constantly rotated in any suitable manner so that as soon as a can is gripped between the holders 48 and 49 it begins to rotate.

Just above the rotary holders is mounted a frame, 65, carrying suitable brushes for pressing the labels against the surface of the cans when the latter are rotated. I have found the most successful arrangement of brushes to be that illustrated, there being two short brushes, 66 and 67, extending diagonally from points near the middle of a can arranged in the holders to the ends, the inner ends of the brushes being in advance so that the labels will first be engaged at this point. Beyond the brushes 66 and 67 is a third brush, 68, arranged parallel with the axis of the rotary holder and preferably of a length equal to the width of a label.

When a can is inserted in the rotary holder its label is still trailing behind and resting upon the apron in rear of the seat from which the can has just been lifted, the paste 90 on the label causing it to adhere to the apron. The direction of rotation of the holders is such that the label is drawn over the top of the can and beneath the brushes. The brushes 67 first engage with the central 95 portion of the unattached part of the label and press it firmly against the can. The next portions of the label to be acted upon are those somewhat nearer the ends of the can, a progressive action taking place from 100 the center toward the ends with the result that the label is not only pressed against the can but is smoothed and drawn outwardly in both directions from the center so as to make it tight, smooth and even. As the label 105 is being wrapped on the can, its trailing end is drawn forwardly across the supporting apron, the adhesion of the paste offering sufficient resistance to keep the label taut. Consequently by having allowed the moisture in the paste to soak into the label and permitted the label to stretch, working progressively on the stretched label from the middle of the can toward the ends while it is held taut, the label will be secured about 110 the can in the most perfect manner possible and, upon subsequently drying will virtually form an integral part of the can. The long straight brush, 68, serves to press down the extreme central portion of the label and 115 also serves a useful purpose in causing the label to adhere firmly throughout the length of the can after it has been pressed in contact by the primary brushes.

The cans illustrated in the drawings are 125 of the type having the ends covered by flanged caps and the labels are made long enough to overlap these caps. My improved method of attaching the labels is of particular advantage in connection with this type 130

of cans because the dampened label lends itself readily to the abnormal stretching which is necessary to compensate for the enlarged circumference of the capped ends and makes it possible to apply the labels smoothly, not only over the body of the can, but over the flanges of the caps, without danger of tearing the labels; the result being that the cans are not only neatly labeled but are hermetically sealed by means of the labels.

After the labeling of a can has been completed the can drops into its seat and the conveyer carries it during its next step in front of the discharge belt, 13. Just at the inner end of the discharge belt 13 is an ejector comprising a bar, 70, in the form of an inverted U the yoke of which extends across the conveyer at a sufficient height to permit the passage of a can; the lower end of the outer arm of which is fixed to a shaft, 71, journaled so as to rotate about an axis parallel with the direction of movement of the adjacent portion of the conveyer, and there is a laterally projecting finger, 72, extending from the lower end of the inner arm below the lowermost point of a can held in the conveyer. When the conveyer comes to rest, the shaft 71 is turned so as to lift the inner end of the ejector and cause the finger thereon to engage with the underside of the inner end of a can, if there be a can in the seat opposite the inner end of the discharge belt, and lifting the can into an upright position upon the discharge belt which carries it out of the machine.

I have heretofore described only the main features of the machine since they do not depend upon any particular design of frame; and the construction and arrangement of the shafting, gearing, and other connecting mechanisms may be variously changed. I shall now briefly refer to some of these minor structural details.

The main frame of the machine may conveniently consist of a pedestal, 75, for supporting the idle sprocket wheel, 3, of the conveyer and the adjacent ends of the stationary guides, and a broad substantial base, 76, supporting the opposite end of the conveyer and all of the remainder of the mechanism. In the arrangement shown, there is a main shaft, 77, extending horizontally across and supported by the frame member 76, this shaft having on one end a suitable driving pulley, 77^a, and having on its other end a sprocket wheel, 78, driving a sprocket chain 79 which in turn drives a sprocket wheel 80 splined to the shaft 46 of the rotary holder by means of which the labeling of the cans is completed. By splining the sprocket wheel 80 to the shaft 46, the shaft is free to move in the lengthwise direction without requiring the sprocket wheel to have corresponding movements. The shaft 63 on which the controlling cams for the rotary

can holder are mounted is a continuously driven shaft. On it may conveniently be mounted the cam 23 which operates the cradle 19. The shaft 63, being a continuously driven shaft, may be connected directly to the main shaft 77 by a suitable gear wheel, 81, and pinion, 82, causing the shaft 63 to revolve more slowly than the main shaft.

The swinging shelf for delivering the cans to the main conveyer may also be connected to a continuously driven shaft. In the arrangement shown, the swinging shelf 14 is fixed upon a horizontal shaft, 83, having a rocker arm, 84, which is in turn connected to a crank, 85, fixed upon a shaft, 86. The shaft 86 has on one end a bevel gear wheel, 87, meshing with a complementary wheel, 88, on a shaft, 89, extending at right angles to the shaft 86 and the main shaft 77. A reducing bevel gear connection, 90, between the main shaft 77 and the shaft 89 serves to drive the latter shaft and through it and the connections just described oscillate the swinging shelf in proper time relations to the remaining mechanism.

The shaft 89 is arranged in proximity to the discharge point of the machine and lies parallel with the supporting shaft 71 of the ejector. On the shaft 89 is an eccentric 91, provided with a rod, 92, which is connected to a rocker arm, 93, on one end of the ejector shaft; the shaft 89 serving to oscillate the ejector in proper time relation to the movements of the conveyer.

Since the main conveyer and the rollers of the label feeding mechanism are driven intermittently in unison with each other, both may conveniently be driven from an intermittently rotating shaft, 96, arranged parallel with the main shaft 77. In the arrangement shown, there is on the main shaft a gear wheel, 97, meshing with a gear wheel, 98, loose on the shaft 96. A suitable clutch device, 99, (best shown in Figs. 11 and 12), serves to clutch the gear wheel 98 to its shaft when desired. This clutch device is preferably one of the type which, when thrown in, allows the shaft 96 to make a complete revolution and is then automatically thrown out again. The clutch may conveniently be controlled by a cam, 100, fixed to the constantly driven cam shaft, 63, and actuating a suitable clutch controlling member, 101. With this arrangement the shaft 96 is driven intermittently in definite time relation to the movements of the main shaft and the cam shaft 63. On the outer end of the shaft 96 is a sprocket wheel, 102, around which passes a sprocket chain, 103, adapted to drive a sprocket wheel, 104, connected with and actuating the gear train, 105, between the rollers of the label feeding mechanism. On the inner end of the shaft 96 is a bevel pinion, 106, meshing with a

bevel gear, 107, on the supporting shaft 108 for the driving sprocket wheel 2 of the main conveyer.

The rotary brush, 18, is preferably driven continuously and this may conveniently be accomplished by passing a belt, 109, over a pulley, 110, on the main driving shaft and over a pulley, 111, on the supporting shaft 112 for the brush.

19 In order that the brush 18 may conveniently be removed for the purpose of cleaning it or repairing it, I mount its supporting shaft in two brackets, 113 and 114, the bracket 113 receiving one end of the shaft 112 and the bracket 114 lying between the brush and the pulley 111. The bearing, 115, in the bracket 114 is larger in diameter than the shaft 112 and, in order that the shaft may fit the bearing, it is provided with two 23 separated annular flanges, 116, large enough to fill the bearing. A slot, 117, opens out of the top of the bearing 115, the slot being wide enough to permit the passage of the brush shaft. When the brush shaft is properly assembled in its bearings, a pin, 118, is inserted in the bracket 114 between the two collars or flanges, 116, thus holding the shaft against endwise movement without interfering with its rotary movements. 25 When it is desired to remove the brush, the pin 118 is withdrawn and the shaft is shifted endwise far enough to bring the collars or flanges 116 to one side of the bracket 114, whereupon the shaft may be 29 lifted out of the bearing through the slot 117.

Another useful detail to which I have not heretofore referred is a device, best shown in Fig. 7, associated with the rotating can holder for the purpose of insuring that the cans will be freed from the cup-shaped holding devices when the latter are drawn apart. This device consists of disks, 120, one of which is arranged in each of the 45 cup-shaped members 48 and 49, and springs, 121, arranged behind the disks and tending constantly to force them out of the cups. When the holder is closed upon the can the springs 121 are compressed and the disks 50 120 are forced inwardly. When the holder is opened, the springs 121 force the disks outwardly so as to bring the ends of the can clear of the cups, thus taking away all support for the can and insuring that it will 55 drop down on its seat. The outward movement of the disks may conveniently be limited by headed pins or screws, 122, extending from the disks through openings in the members 48 and 49, the movement of the 60 disks in the outward direction being limited by the heads of the pins or screws.

In Figs. 9 and 10 I have illustrated a convenient arrangement for maintaining a constant level of the paste in the well 33. Arranged at one side of the well and connected

thereto by a pipe, 125, is a cup, 126. Secured to the cup is an annular member, 127, having a seat, 128, for receiving an inverted bottle, 129, adapted to contain a supply of paste. When the well is empty and a full 70 bottle is placed upon the seat with its open mouth down, the paste will flow out of the bottle into the cup and from there into the well, the paste level in the well and in the cup being the same. The paste continues to 75 flow until the paste in the cup rises high enough to close the mouth of the bottle, whereupon the flow of paste ceases. As the paste is consumed during the operation of the machine, the level in the well and in the 80 cup begins to fall and uncovers the mouth of the bottle, whereupon the paste again begins to flow out of the bottle and maintains the normal level in the well. It will be seen that the level of the paste in the well is 85 controlled by the vertical adjustment of the bottle and therefore, in order that the paste level in the well may be varied at will, I have made the bottle-supporting member 127 adjustable in the vertical direction; this being conveniently accomplished by forming in the vertical portion of the member 127 a diagonal slot, 130, through which extends a screw, 131, the screw being screw threaded into the wall of the cup. By loosening the 90 screw and turning the member 127 in one direction or the other, the bottle may be raised or lowered in order to fix the paste level in the well at any desired height.

100

I claim:

1. In combination, mechanism for delivering a paste-covered label and partially attaching it to a can along a narrow strip at one end of the label, means for thereafter holding the main portion of the label out of 105 contact with the can for an interval of time sufficient to permit the moisture in the paste to impregnate the label, and means for completing the attachment of the label to the can at the end of said interval of time.

110

2. In combination, mechanism for delivering a paste-covered label and partially attaching it to a can along a narrow strip at one end of the label, mechanism for acting on the can and label to complete the attachment of the label, and means for actuating said mechanisms with a sufficient time interval between the partial attaching of the label and the completing of the attachment to permit the moisture in the paste to impregnate the label.

115

3. In combination, means for delivering a paste covered label and attaching it at one end only to a can, a conveyer for carrying the can from the aforesaid means and retaining it a sufficient time to permit the moisture in the paste to soak into the label, and means for receiving the can from the conveyer and completing the attachment of the label thereto.

120

125

130

4. In combination, a conveyer, separated can seats on the conveyer, an apron extending rearwardly from each seat, means adjacent to the conveyer for delivering paste-covered labels to cans resting in said seats and attaching the front edges of the labels to the cans, and additional means at a remote point adjacent to the conveyer for completing the attachment of the labels to the cans.

5. In combination, a conveyer, separated can seats on the conveyer, an apron extending rearwardly from each seat, means adjacent to the conveyer for delivering paste-covered labels to cans resting in said seats and attaching the front edges of the labels to the cans, and remote means adjacent to the conveyer for receiving the cans and completing the attachment of the labels thereto.

6. In combination, a conveyer provided with separated seats each adapted to hold a can to be labeled, means adjacent to the conveyer for delivering paste-covered labels to cans in said seats, and remote means for receiving the cans from the conveyer and acting on the cans and labels to complete the attachment of the labels to the cans.

7. In combination, a conveyer having separated seats for receiving cans, means above the conveyer for delivering a paste-covered label to each can, a rotary brush for attaching the advance end of each label to its can, and remote means for completing the attachment of the labels to the cans.

8. In combination, a movable conveyer having separated seats for holding cans, means above the conveyer for feeding a paste-covered label to each can and attaching the advance end of the label to the can, and means for receiving the cans from the conveyer and pressing the label around the same.

9. In combination, a movable conveyer having separated seats for holding cans, means above the conveyer for delivering paste-covered labels in the direction of movement of the conveyer and applying the front end of each label to a can, and remote means for receiving the cans and pressing the labels around the same.

10. In combination, means for delivering paste-covered labels and attaching one end of each label to a can, means for acting on the can and completing the attachment of the label thereto, a conveyer having separated can receiving seats, and means for intermittently moving the conveyer and bringing it to rest between successive movements with one of the can seats in proximity to each of the aforesaid means.

11. In combination, a conveyer having separated seats for receiving cans, means above the conveyer for delivering paste-covered labels one at a time, means for moving the conveyer intermittently and stopping it between successive movements with one of

the seats in a position to permit the advance end of a label to project over a can resting in the seat, means for projecting the overhanging end of each label upon the corresponding can so as to partially secure the label thereto, and means for receiving the cans from the conveyer and completing the attachment of the labels to the cans.

12. In combination, mechanism for applying wet paste to a label and attaching the label to a can throughout a narrow strip at one end of the label, means for thereafter holding the greater portion of the label out of contact with the can for a sufficient period of time to permit the moisture in the paste to soak into the label and cause the label to stretch after it has been partially attached to the can, and mechanism including means for rotating the can about its axis for thereafter completing the attachment of the label to the can.

13. In a machine of the character described, a revoluble holder for a can, and brushes arranged diagonally in a plane tangential to a can in the holder in position to engage with a label on the can and smooth and press the same about a can being rotated by the holder.

14. In a machine of the character described, a rotatable holder for receiving and revolving a can about the axis of the can, a brush having approximately the length of a can and arranged parallel with the axis of the can, diagonal brushes in advance of the aforesaid brush arranged in a plane tangential to a can in the holder, said brushes being positioned to engage with the surface of a can in the holder.

15. In a machine of the character described, a rotary can holder comprising two separated can-engaging members adapted to revolve a can about the axis of the latter, a brush between the members arranged parallel with the axis of rotation, diagonal brushes arranged symmetrically with respect to an intermediate plane at right angles to the axis of rotation, said brushes being positioned to engage with the surface of a can located in the holder.

16. In a machine of the character described, a rotary can holder comprising two separated can-engaging members adapted to revolve a can about the axis of the latter, a brush between the members arranged parallel with the axis of rotation, diagonal brushes arranged symmetrically with respect to an intermediate plane at right angles to the axis of rotation, said brushes being positioned to engage with the surface of a can located in the holder, and means for securing the advance end of a paste-covered label to a can and delivering the can to the holder.

17. In combination, an endless conveyer having separated seats for receiving cans,

- means for intermittently moving the conveyer through a distance equal to the distance between consecutive seats, means for delivering a can into each seat when it reaches a predetermined point, means for delivering and attaching one end only of a paste-covered label to the can when the last mentioned seat reaches a second predetermined point, and means for completing the attachment of the label to the can when it reaches a third predetermined point. 5
18. In combination, an endless conveyer having separated seats for receiving cans, means for intermittently moving the conveyer through a distance equal to the distance between consecutive seats, means for delivering a can into each seat when it reaches a predetermined point, means for delivering and attaching one end only of a 10 paste-covered label to the can when the last mentioned seat reaches a second predetermined point, means for completing the attachment of the label to the can when it reaches a third predetermined point, and means for removing the can from the conveyer when it reaches a fourth predetermined point. 15
19. In combination, a conveyer, separated can seats on the conveyer, supports on the conveyer behind said seats, means for delivering paste-covered labels to cans resting in said seats and attaching the front edges of the labels to the cans at such points thereon as to permit the rear end of the labels to rest on said supports, and mechanism at a point remote from the aforesaid means for causing the attachment of the labels to the cans to be completed. 20
20. In a machine of the character described, a movable conveyer having separated can receiving seats, supports on the conveyer adjacent to said seats, means for attaching one end of a paste-covered label to a can in one of said seats when the can reaches a predetermined point and laying the remainder of the label on the corresponding support, and means for completing the attachment of the label to each can when it reaches a second predetermined point. 25
21. In a machine of the character described, a movable conveyer having separated can receiving seats, an apron arranged above the conveyer in rear of each of said seats, means for attaching the advance end of a paste-covered label to a can when it reaches a predetermined point and laying the remainder of the label upon the corresponding apron, and means for completing the attachment of the label to each can when it reaches a second predetermined point. 30
22. In a machine of the character described, a movable conveyer having separated can receiving seats, an apron arranged above the conveyer in rear of each of said 35 seats, means for attaching the advance end of a paste-covered label to a can when it reaches a predetermined point, means for laying the remainder of the label upon the corresponding apron, and means for completing the attachment of the label to each can when it reaches a second predetermined point. 40
23. In a machine of the character described, a conveyer for cans to be labeled, mechanism for applying paste to a label and feeding the label toward a can on the conveyer, means for pressing one end of the label against the can to attach the same, and means for actuating said conveyer and said mechanism so as to cause said mechanism to feed the label at a speed somewhat greater than the speed of the conveyer. 45
24. In a machine of the character described, a conveyer for cans to be labeled, means for intermittently moving the conveyer, mechanism for applying paste to a label and feeding the label in the direction of movement of the conveyer while the conveyer is moving, and means for attaching the advance-end of the label to a can on the conveyer while the conveyer is stationary, said mechanism being constructed and arranged to feed the label at a speed slightly in excess of the speed of the conveyer. 50
25. In a machine of the character described, a movable conveyer arranged to carry cans to be labeled, mechanism for applying paste to a label and feeding it in the direction of movement of the conveyer, means for intermittently actuating said conveyer and said mechanism in unison with each other and stopping the conveyer in positions to bring a can in operative relation to the advance end of a label which is being fed, and means for attaching the advance end only of a label to a can on the conveyer while the conveyer is stationary. 55
26. In a machine of the character described, a conveyer having seats for receiving cans to be labeled, mechanism for delivering paste-covered labels one at a time, means for intermittently actuating the conveyer and stopping it in positions adapted to bring a can beneath one end of a label which is being delivered, means for attaching the advance end of such label to the can while the conveyer is stationary and additional means acting on the can to complete the attachment of the label thereto. 60
27. In a machine of the character described, a conveyer having seats for receiving cans to be labeled, mechanism for delivering paste-covered labels one at a time, means for intermittently actuating the conveyer and stopping it in positions adapted to bring a can beneath one end of a label which is being delivered, a rotating brush in position to overlie the advancing label, and 65

means for raising the can which is to receive the label to carry the advance end of the label into contact with the brush.

28. In combination, a conveyer adapted to hold cans to be labeled, means for attaching one end of a paste-covered label to a can on the conveyer, and means for lifting the can from the conveyer and wrapping the label around the same.

10 29. In combination: a conveyer adapted to receive cans to be labeled; means for attaching one end of a paste-covered label to a can on the conveyer; means for lifting the can from the conveyer, wrapping the label about the same and returning the can to the conveyer, and means for discharging the can from the conveyer.

30. In combination: an endless conveyer adapted to carry cans to be labeled, means for placing a can on the conveyer; means for partially attaching a paste-covered label to the can at a predetermined point in the movement of the conveyer; means for lifting the partially labeled can from the conveyer and completing the attachment of the label, and returning the can to the conveyer; and means for finally discharging the can from the conveyer.

31. In combination, mechanism for delivering a paste-covered label and partially attaching it to a can along a long narrow area, mechanism for acting on the can and label to complete the attachment of the label, and means for actuating said mechanisms with a sufficient time interval between the partial attaching of the label and the completing of the attachment to permit the moisture in the paste to impregnate the label.

32. In combination, mechanism for delivering a paste-covered paper label and partially attaching it to a can throughout a long narrow area extending along a line running parallel with the grain of the paper, mechanism including means for revolving the can on its axis for completing the attachment of the label to the can, and means for delaying the action of the latter mechanism long enough after the partial application of the label to permit the moisture in the paste to soak into the label before the label is completely attached.

33. In combination, a conveyer adapted to carry cans to be labeled, mechanism for

feeding a paste-covered label into proximity to a can on the carrier, means for intermittently operating said conveyer and said mechanism in unison with each other and for causing the conveyer to come to rest with a can underlying the advance end of a label which is still held at its rear end in said mechanism, and a rotating brush in position to engage the advance end of the label and press it upon the can while the can and the label are stationary.

34. In combination, a conveyer adapted to carry cans to be labeled, mechanism for feeding a paste-covered label into proximity to a can on the carrier, means for intermittently operating said conveyer and said mechanism in unison with each other and for causing the conveyer to come to rest with a can underlying the advance end of a label which is still held at its rear end in said mechanism, and a rotating brush in position to engage the advance end of the label and press it upon the can while the can and the label are stationary, the brush rotating in the direction tending to draw the label out of the feeding mechanism.

35. In a machine of the character described, a device having a can receiving seat, a member arranged adjacent to said seat, means for laying on a can in said seat a paste-covered label having a portion resting on the aforesaid member, and means acting on said can to rotate the same in a direction to draw the label across said member on which it is resting and affix it around the can.

36. In a machine of the character described, a member provided with a can receiving seat, an apron arranged in proximity to the seat, means for attaching one end of a paste-covered label to a can in said seat and laying the other end on said apron with a paste-covered side in engagement with said apron, and means acting on the can to rotate the same in a direction to draw the label across the apron and affix it around the can.

In testimony whereof, I sign this specification in the presence of two witnesses.

JESTER L. LADD.
